(57) **CLAIM**

The ornamental design for the digital multifunction printer, as shown and described.

DESCRIPTION

FIG. 1 is a perspective view of a digital multifunction printer showing our new design;

FIG. 2 is a front view of the digital multifunction printer;
FIG. 3 is a rear view of the digital multifunction printer;
FIG. 4 is a right view of the digital multifunction printer;
FIG. 5 is a left view of the digital multifunction printer;
FIG. 6 is a plan view of the digital multifunction printer; and,

FIG. 7 is a bottom view of the digital multifunction printer. The dot-dash broken lines immediately adjacent to the shaded areas depict the bounds of the claimed design, while all evenly spaced broken lines are directed to environment. The broken lines form no part of the claimed design. The item is a multifunctional machine that combines the functions of a copier, scanner, and printer.
